CLAIM

The ornamental design for a networking device for a streetlight, as shown and described.

DESCRIPTION

FIG. 1 is a top, front, right side perspective view of a networking device for a streetlight showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

The broken lines in FIGS. 2, 3, and 5-7 depict portions of the article that form no part of the claimed design.

1 Claim, 5 Drawing Sheets
